US0D1088959S

(12) **United States Design Patent** (10) **Patent No.:** **US D1,088,959 S**
(45) **Date of Patent:** **** Aug. 19, 2025**

(54) **AUTONOMOUS VEHICLE**

(71) Applicants: **Hyundai Motor Company**, Seoul (KR); **Kia Corporation**, Seoul (KR)

(72) Inventor: **Jong Myeong Yun**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/944,378**

(22) Filed: **May 28, 2024**

(30) **Foreign Application Priority Data**

Dec. 28, 2023 (KR) 30-2023-0053570

(51) **LOC (15) Cl.** **12-06**

(52) **U.S. Cl.**

USPC **D12/86**

(58) **Field of Classification Search**

USPC ... D12/1, 36, 37, 38, 39, 40, 41, 42, 43, 86; D21/533, 540, 541, 548, 552

CPC B60L 2200/26; B29C 66/82263; B61D 19/02; B61C 7/00; B61F 3/08

See application file for complete search history.

(57) **CLAIM**

The ornamental design for autonomous vehicle as shown and described.

DESCRIPTION

FIG. 1 is a perspective view of the subject design as viewed from the front.

FIG. 2 is a front view of the subject design.

FIG. 3 is a rear view of the subject design.

FIG. 4 is a left side view of the subject design.

FIG. 5 is a right side view of the subject design; and,

FIG. 6 is a top view of the subject design.
